UNITED STATES PATENT OFFICE.

JAMES E. LINDSEY, OF ELMO, TEXAS.

COTTON-CHOPPER.

SPECIFICATION forming part of Letters Patent No. 240,598, dated April 26, 1881.

Application filed October 12, 1880. (Model.)

To all whom it may concern:

Be it known that I, JAMES E. LINDSEY, of Elmo, in the county of Kaufman and State of Texas, have invented certain new and useful 5 Improvements in Cotton-Choppers; and I do hereby declare that the following is a full, clear, and exact description of the invention, which will enable others skilled in the art to which it appertains to make and use the same, reference 10 being had to the accompanying drawings, which form a part of this specification.

Figure 1 is a perspective view of a cotton-chopper embodying my improvements. Fig. 2 is a vertical longitudinal sectional view, and 15 Fig. 3 is a plan view.

This invention has relation to cotton-choppers; and it consists in the improvements in the construction of the same hereinafter fully described and particularly pointed out in the 20 claim.

Referring by letter to the accompanying drawings, A designates the transverse perforated axle, and B B end blocks adjustably secured thereto by bolts or screws, and C C 25 the rearwardly-projecting arms, which form the bearings for the supporting-wheels D D.

E E designate the choppers or cultivators, secured to the curved standards F, fixed to the under side of the axle A. The axle A is 30 provided with holes, so that the choppers or cultivators may be adjusted thereon to bring them nearer together or place them farther apart, as may be desired, to change the implement from a chopper to a marker or cultivator. The end blocks may also carry teeth or 35 plows, and may be adjusted on the axle. The wings of the choppers E have vertical upwardly-extending flanges G, to prevent the portion of cotton removed from falling on that which 40 is to remain.

H H designate two parallel beams secured upon the axle, and to which the pivoted tongue I and driver's seat J are secured. The tongue I is pivoted between the forward ends of the beams H, and its rear end is bifurcated and 45 connected, by a link, K, to a double crank, L, having bearings M on the beams H, and provided at one end with a lever, N, within reach of the driver's seat, and arranged to engage a rack, O, secured to the axle A at one side of 50 the beams H.

By operating the lever N the choppers or plows, as the case may be, may be thrown in or out of the ground at pleasure.

The construction and operation of this device will be readily understood from the foregoing description when taken in connection with the accompanying drawings. It is simple and inexpensive, and may be readily changed from a cotton-chopper to a cultivator by simply adjusting the plows. 55

Having thus fully described my invention, what I claim as new, and desire to secure by Letters Patent, is—

In a cotton-chopper, the axle A, provided 65 with adjustable end blocks, B, having rearwardly-projecting arms C C, forming bearings for wheels D, the plows or choppers E, adjustable to or from each other on the axle, the parallel beams H, and pivoted tongue I, provided with crank L, lever N, and rack O, as shown and described. 70

In testimony that I claim the foregoing as my own I have hereto affixed my signature in presence of two witnesses.

J. E. LINDSEY.
